UNITED STATES PATENT OFFICE.

NOBLE S. MCKINSEY AND ANTON R. NELSON, OF SUSANVILLE,
CALIFORNIA.

SELECTIVE TELEPHONE.

No. 820,064.

Specification of Letters Patent.

Patented May 8, 1906.

Application filed December 27, 1904. Serial No. 238,276.

To all whom it may concern:

Be it known that we, NOBLE S. MCKINSEY and ANTON R. NELSON, citizens of the United States, residing at Susanville, in the county of Lassen and State of California, have invented certain new and useful Improvements in Selective Telephones, of which the following is a specification.

Our invention relates to improvements in selective telephones, the object of the invention being to provide a telephone of such construction that a number of them can be used on the same line, and a number of such lines can be connected to a central station, and in which the talking between any party on one line and a party called on another line shall be absolutely secret and under the control of the party calling.

A further object is to obtain this result with a comparatively simple and inexpensive construction.

In the accompanying drawings, Figure 1 is a view of the mechanism on the inner side of the door of the telephone-box, which box contains the battery, here not shown. Fig. 2 is an enlarged view of the principal part of the operating mechanism. Fig. 3 is a diagrammatic view of the system as a whole. Fig. 4 is a horizontal section showing the selecting mechanism in top plan view. Figs. 5 and 6 are broken front views in two different positions, showing the control of the rotating mechanism by the magnets. Fig. 7 is a broken perspective view of the ends of the levers operated by the armatures. Fig. 8 is a perspective view of said levers detached from said armatures. Figs. 9 and 10 are broken front views showing different positions of the line-controller and of the "busy" signal regulated thereby. Figs. 11 and 12 are corresponding front views of the busy signal. Fig. 13 is a diagrammatic view of the connections in the telephone. Fig. 14 is a diagrammatic view in a simple form of the connections of the system. Fig. 15 is a perspective view of the jack, and Figs. 16 and 17 are perspective views of the plugs.

General character of the system.—The system is one having a central station and an indefinite number of pairs of wires proceeding therefrom, and each pair of wires has a convenient number of parties' telephones connected therewith. The number of telephones on each pair of wires will depend upon the de-

mand for service and the tariffs paid by the parties. In Fig. 3 there are shown only two of such lines or pairs of wires leading from the central station; but it is to be understood that there may be any number thereof. With each line are shown connected only two parties' telephones; but any suitable number may be so connected. Primes are added to the numerals in this figure to conveniently distinguish the circuits and parts on the right of the figure from those on the left. Of the two line-wires 1 2 for each group of parties on the same line, the wire 1 is grounded at central, as shown at 3, and has therein a main battery 4 and a resistance 5. This resistance is greater than that of any talking-circuit in the system to prevent the talking passing said resistance.

Calling central.—Any party lifting his receiver 6 from the automatic hook 7 automatically calls central in the following manner: Said hook then rises under the action of a spring 8, and a pin 9 thereon engages the under side of the horizontal end of a resilient lower portion 10 of a line-controller 11, the main body of the line-controller being pivoted on a shaft 12, extending between the front and rear plates of the frame 13 of a clockwork mechanism 15. A light spring 16, coiled about the shaft 12, having one end hooked over a bracket 17 on the door 18 of the telephone-box 19, and the other end passed through an aperture in an extension 20 of said line-controller 11, normally moves the upper part of said controller upward and the lower part downward. When the line-controller 11 is thus raised, its resilient portion 10 is brought into contact with two spring-contacts 21 22. The lower contact 21 is connected by a wire 23 with a bent or plate bracket 24, (forming a support for three pairs of spring-contacts hereinafter described,) which plate 24 is again connected by a wire 25 with the upper terminal 26 of a resistance-coil 27, the lower terminal 28 of said coil being connected by a wire 29 to a hinge 30 of the door of the telephone-box, whence a wire 31 leads to ground at 32. A calling-circuit is thus completed as follows: ground 32, wire 31, hinge 30, wire 29, coil 27, wire 25, plate 24, wire 23, contact 21, line-controller spring 10, clockwork-frame 13, wire 33, hinge 34, wire 35, wire 2, to central, coil 36 of calling-drop magnet, wire 1, resistance 5, battery 4,

ground 3. The calling-drop magnet is thus energized, releasing the drop and calling central.

Talking to central.—Central now inserts a plug 37, connected to a wire 62 of her cord, in the jack 39 of the calling-party's line, thus connecting the two wires of her plug-cord with the wires 1, 2, and thus connecting her talking-circuit 40, through the listening-key 41, with the talking-circuit of the calling party. This circuit was completed by the lifting of the hook, as follows: Upon the bracket 24 are secured seven contact-plates, separated by insulating-plates 42. Three of these, 44 46 48, are spring-plates and movable, being longer than the others and their ends being inserted in notches in an insulating-block 50, secured to a metallic plate 51, bent at right angles and pivoted, as shown at 52, on the door 18. The edge of this plate is engaged and depressed by the automatic hook 7 when down. These three plates 44 46 48 are therefore depressed when the telephone is on the hook and rise by their own spring when the telephone is lifted. Therefore when the calling party lifts his hook the plate 44 on rising contacts with the plate 43 above it and the plate 46 breaks contact with the plate 47 below it and contacts with the plate 45 above it. This connects the party's secondary talking-circuit with the talking-circuit at central as follows: receiver 6, wire 54, connection 55, wire 56, plate 45, plate 46, wire 59, clockwork-frame 13, wire 33, hinge 34, wire 35, line-wire 2, spring 60 of the jack, tip 61 of plug 37, wire 62, wire 63, listening-key 41, talking-circuit 40, listening-key 41, wire 64', condenser 65, wire 66, shank 67 of plug 37, ring 68 of jack 39, contact 69, spring 70, line-wire 1, wire 71, hinge 72, wire 73, plate 43, plate 44, wire 74, secondary coil 75, wire 76, condenser 77, wire 78, terminal 79, wire 80, receiver 6. The primary talking-circuit of the calling party is also completed as follows: battery 81, wire 82 to point 83, wire 84 to primary coil 85, wire 86, transmitter 87, wire 88, binding-post 89, wire 90 to point 55, wire 56, plate 45, plate 46, wire 59, clockwork-frame 13, line-controller spring 10, contact 22, wire 91 to battery 81. In this way the calling party may be placed through his jack in talking communication with central. This primary talking-circuit is supplied from the same battery 81 as the bell-circuit, but provision is made for continuously closing the bell-circuit, and thus preventing the bell ringing whenever the primary talking-circuit is closed and at the same time throwing off a shunt which was around the receiver and passes through the bell-armature, this shunt being provided, as hereinafter described, in order to obtain secrecy on the line, the branch through the bell-coils proceeding as follows: point 83, wire 92, terminal 93, wire 94, bell-coils 95, wire 96, hammer-contact 96, wire 98, terminal 99, wire 100 to point 55, whence the circuit proceeds through the battery 81 to the point 83 in common with the primary talking-circuit. Thus the current from the battery divides and proceeds partly through the primary talking-circuit and partly through the bell-magnet coils, and thus whenever the primary talking-circuit is closed the bell-magnets are energized and the hammer is held close up to the gong and the shunt around the receiver is opened at 97, this shunt being as follows: point 79, wire 118, binding-post 145, hammer-spring contact 146, hammer-spring 101, spring-contact 182, contact 97, wire 98, binding-post 99, wire 100, point 55. This spring-contact 182 is attached to the bell-hammer armature 147 and vibrates therewith and when the bell-coils are energized is withdrawn from the contact 97, breaking the shunt around the receiver and allowing the receiver to be used.

Ringing up called party.—Central having ascertained from the calling party the number wanted, inserts the plug 37' into the other jack 39' of the line on which is the called party's telephone. She can thereby complete a circuit through the selector-magnets of all the parties on the line on which is the called party's telephone, said circuit passing to the ground at central and also at the calling-party's station. On inserting contacts 102 102' of ringing-key 103 at 104 104' the circuit is as follows: ground 32, wire 31, hinge 30, wire 29, resistance 27, wire 25, plate 24, wire 23, spring-contact 21, line-controller 100 spring 10, clockwork-frame 13, wire 33, hinge 34, wire 35, wire 2, spring 60 of jack 39, tip 61 of plug 37, wire 62, contacts 104 102, wires 105 106, ringing-key 103, wires 106' 105', contacts 102' 104', wire 62', tip 61', spring 60', wire 2', the circuit then dividing and passing at each station through wire 33', hinge 34', wire 33', wire 107', magnet-coil 108', wire 109', hinge 72', wire 71', then to the common wire 1' contact 69', wire 1', resistance 5', battery 1' to ground at 3. All coils that are bridged on the lines have the same resistance, so that a proportional amount of the current also passes through the calling-magnet coils 36', releasing the drop for the called line.

It is to be understood that the insertion of the plug 37' in the jack does not break the contact 69'. This is only broken when a third plug 111 is used, this plug being used when the party called is on the same party-line as the party calling. In the latter case the plug 37 is removed and is replaced by the plug 111, the tip 112 of which contacts with the spring 70 of the jack 39 of the line of the calling party and at the same time breaks the contact 69, while the shank 113 contacts with the ring 68 of said jack. In that case one line is connected to ground at 3 at one end and the other line 32 at the calling-party's station and the selector-magnets are bridged

between the two wires at all stations on the line of the calling party. In either case central now sends a number of impulses corresponding to the number of the called party on his line. This central does by operating the ringing-key 103 the required number of times, then leaving it closed. The effect of each closure is to energize the magnet 108, but with a comparatively weak current, owing to the resistance 27 being in the circuit. The magnet 108 has two armatures 121 122, the armature 121 being nearer the magnet than the armature 122. The armature 121 is attached to levers 123, fixedly secured on a shaft 124, rocking in the clockwork-frame 13, said levers being connected at their other ends by a cross-pin 125, which passes through a slot 126, formed in the end of a lever 127, loosely pivoted on the shaft 124, the other end of said lever 127 being attached to the armature 122, to which are also attached side supporting-bars 128, loosely pivoted on the shaft 124. The end of the lever 127 is bent and otherwise shaped to form an escapement 119 for a small wheel 129, rotated by a pinion 130, driven by a gear-wheel 131, rotated by a train 132 of gears from a main spring 133. This train of gears is such that the movement of the wheel 129, when released by the escapement 119, is very rapid. Said wheel 129 has two diametrically opposite studs 134 thereon. In the position of rest, one of these studs rests against a broad stop 135, formed by bending the end of the lever 127 inward at right angles. When the magnet 108 is energized by a weak current sufficient to draw the armature 121, but not the armature 122, close to the magnet, the stop 135 rises, permitting the stud 134 to pass underneath it and the wheel 119 to turn, which it does from the force of the spring 133, transmitted through the train 132, gear 131, and pinion 130; but the wheel 129 makes only a part of a revolution at a time, for the other stud 134 now strikes a narrow stop 136, which, being just below the stop 135, has, by the rise of the stop 135, been brought into position to arrest said other stud 134. The stop 136 is spaced longitudinally of the lever from the stop 135, allowing the stud 134, which rested against the stop 135, to pass between the stops 135 136 and then under and around the stop 135. When a break is made in the circuit, the stop 136 falls and the stud 134, which was resting against it moves slightly forward and rests against the stop 135.

Each make and break of the circuit through the coils of the magnet 108 advances the wheel 129 half a revolution, and therefore advances the wheel 131 through a comparatively small angle, depending upon the ratio of the diameters of the wheel 131 and the pinion 130. After a certain number of 65. makes and breaks have thus been made a

finger 137, extending from the shaft of the wheel 131, has moved through such an angle that upon the last closure of the circuit it rests in contact with an arm 138, extending from a shaft 139 in a hollow standard 140, 70 said arm being normally held by a spring 114 against a shoulder 142, formed in the end of the standard. To ring up the called party, therefore, central makes and breaks contact the desired number of times (which will be 75 different for each party on the same line) and the called party's bell-circuit is then closed. The bell-circuit is as follows: battery 81, wire 143 to standard 140, arm 138, finger 137, clockwork-frame 13, wire 59, plate 46, plate 80 47, (the hook being down,) wire 144, point 117, wire 118, terminal 145, spring 101, spring 182, hammer-contact 97, wire 96, bell-coils 95, wire 94, terminal 93, wire 92 to point 83, wire 82, battery 81. The party called on 85 taking down his phone breaks the bell-circuit at the plates 46 and 47 and joins his secondary talking-circuit onto that of the calling party in precisely the same manner as the secondary talking-circuit of the calling party was 90 closed, as already described.

In Figs. 15, 16, and 17 are illustrated the jack 39, the plug 37, and the plug 111. 148 represents the handle of the plug, and 67 the metallic part of the shank thereof, which contacts with the ring 68 of the jack, while the tip 61 contacts with the spring 60 of the jack. In the plug 111 the shank is longer and has a longer insulated portion 149 separating from the tip 112, which contacts with the spring 100 70 and breaks the contact 69 between said spring and the ring 68.

Control of the line.—The calling party has control of the line. If the called party hangs up his receiver, he then breaks the primary 105 talking-circuit, and therefore also the circuit through the bell magnet-coils which is in parallel with the primary talking-circuit and which held the hammer up against the bell, so as to prevent it ringing, and the bell-circuit 110 is then closed as it was before he took down his receiver, so that his bell rings until the calling party hangs up. Thus the called party will know upon hanging up his receiver if the bell continues to ring that the calling 115 party has not finished his conversation.

The called party has no connection with the ground, because the connection on his side of the line is made through the finger 137 and arm 138 and not through the line-controller and contact 22, leading to the ground, as was the case on the calling-party's line. Therefore the called party cannot affect the circuit in any way by removing or replacing his hook, because he cannot close the circuit 125 between the line-controller and the contact 22, but if the calling party hangs up he shunts the resistance 27 by means of the plates 48 49 and wires 164 165, throwing a stronger current into the line and energizing 130

all the magnets on both lines more strongly than before, thereby attracting in each magnet the more distant armature and bringing all the wheels immediately back to their former positions, breaking in the called party's telephone the circuit between the finger 137 and the arm 138. This at the same time operates the clearing-out drop 150, which has a stronger spring than that of the other magnets, although of the same resistance, so that it only operates when a strong current is passed through the line.

When the armature 122 is drawn down to the magnet, both of the stops 135 136 rise to such a position that both of the studs 134 can pass said stops freely, permitting the pinion 130 to revolve rapidly and the gear 131 also to revolve freely until an arm 152, carried by said gear-wheel, impinges against a stop 153, carried on one of the side supporting-bars 128, which brings the gear-wheel 131 to its zero or normal position. All of the gear-wheels on all of the telephones on both lines are by the greater energization of the magnets brought to this zero position, and then upon the release of the armature 122 by the breaking of the circuit, as will be presently described, the stop 135 drops into such a position as to arrest a stud 134 on the pinion 130 and allow the gear-wheel to advance a portion of a step; but since this operation of bringing to the starting position depends upon both of these stops 135 136 being out of the path of the studs 134 a sufficient length of time to permit the finger 152 to revolve with the gear-wheel 131 back to the zero position, it is necessary that this armature 122 be held down a sufficient length of time to allow this movement to take place. Since this movement is caused by shunting the resistance 27, and since the resistance is shunted by connecting the two lower spring-plates 48 49, which is done by the depression of the hook, and since the hook when in its upper position holds up the controller against the contact 21, thereby closing a break in the circuit through the magnets, it would happen unless otherwise provided that the same movement which would shunt this resistance and therefore energize the magnets more strongly would also break the very circuit by which they are energized, and although they might be energized for an instant of time, yet before the magnets would perform their full function the circuit would be broken and the result would be that the armature 122 would not remain down a sufficient length of time to permit the finger 152 to reach the stop 153; but by the armature 122 rising again from the action of its spring and from the fact that the circuit was broken, stop 135 would arrest a stud 134 and stop the gear-wheel before it fully returned to its normal position. To obviate this, there is provided on the back of the gear-wheel a crown-wheel 155, having a

gap 156 therein, through which can fall a pin 157, secured upon the line-controller. This pin is in this gap when the gear-wheel is in its normal or zero position, the line-controller then being supported by a lug 158 thereon, 70 resting upon a pin 159, extending rearwardly from the gear-wheel. The pin 157 is raised out of the gap when the line-controller is raised, so that it lies at a greater distance from the center of the gear-wheel than from 75 the radius of the crown wheel. By the rise of the hook all the magnets on the calling-party's line are energized, causing all the gear-wheels 131 to advance a short distance, carrying the gaps 156 beyond the pins 157, so 80 that the pin of the party calling whose receiver alone is off the hook and whose line-controller has been raised lies on the top of the crown-wheel, and therefore on the calling party hanging up, the line-controller is held 85 up in contact with the contact-spring 22 by the pin 157 traveling on the top of the crown-wheel until the pin 157 again reaches the gap in the crown-wheel and drops through the same, which it only does when the gear-wheel 90 has arrived at its normal or zero position. This insures that the current remains unbroken through the magnets sufficiently long to hold the armature out of the path of the studs 134 until the gear-wheels are all 95 brought to zero.

Secrecy of the talking.—The line is secret both as regards other parties on the calling party's line and others on the called party's line. As to the other telephones on the calling party's line, as soon as the calling party takes down his receiver he energizes all the magnets on his line as well as the magnet of the calling drop at central. These magnets are all of the same resistance, and the battery is increased in strength to produce a uniform current through each magnet according as the number of parties on the line and the number of magnets is increased. All these magnets on his own line being energized with 100 a weak current (the calling party having thrown in the resistance 27) all the armatures 121 are attracted and all the gear-wheels advance a part of a complete step, being arrested by the other studs 134 striking 105 the stops 136. Immediately that the gear-wheels advance the pins 159, extending rearwardly therefrom, move out from under the lugs 158 on the line-controllers, and said line-controllers being no longer supported drop, 110 and the pins 157 thereon drop inward from the gap 156 and are inside the crown-wheels 155. Each such line-controller is then dropped into such position that the extreme end of the resilient portion 10 thereof is 115 passed by untouched by the pin 9 on the hook, so that the other parties on the line can now no longer operate their line-controllers by removing their receivers from the hook. Therefore they cannot close the circuit on the line, 120 125 130

by means of the spring-contact 21, and the primary talking-circuit cannot be made. It is these shunts around the receivers which prevent the other subscribers on the same line from hearing the conversation. Thus the calling party's side of the line is secret. The secondary talking-circuit of any party can always be closed by taking down his receiver, but this will not enable him to hear or talk upon the line for the reasons stated. It will readily be seen that the condensers 77 are introduced into these secondary circuits in order to prevent the current being shunted around the magnets instead of going through them to operate the mechanism. The called party's side of the line is also secret, because the fingers 13 are set at different distances around the gear-wheels, so that they successively make contact with their arms 138, and since the circuit in the called party's telephone passes through this arm and this finger only one party on this line can be on the circuit. Again, as soon as central connects with the called party's line by inserting the plug all the magnets on said line are energized, attracting the armatures 121 with the weak current and causing the gear-wheels to advance a part of a step, thereby causing all the line-controllers to drop out of position to be engaged by the pins 9 upon the hooks, so that no party upon the called party's line can get onto the line except the one which is then called by central by advancing the gear-wheels step by step until the finger 137 of the party desired reaches the arm 138.

Busy signal.—The line-controller has a vertical extension 160, which engages a rearwardly-extending arm 161, pivoted on a vertical shaft 162 and extending into a glass-covered opening in the door of the telephone-box, there carrying a piece of paper having the word "busy" inscribed thereon. A light spring 163 normally draws this arm backward against the vertical extension. When the other controllers on the same line as that of the party calling drop, owing to the pins 159 passing the lugs 158, as aforesaid, and said controllers reach their lowest position, so that they cannot be engaged by the pins 9 upon the hooks, the extension 160 swings to the left, (as viewed from the front of the box,) moving the arm 161 against the action of the spring 162 and bringing the word "busy" opposite to a glass-covered slot in said box. This informs any party on the same line as that of the calling subscriber that the line is in use. When the calling party hangs up and all the gear-wheels return to their normal position, the pins 159 of the other subscribers' telephones engage the lugs 158 on the line-controllers and raise said line-controllers again into such position that they can be engaged by the pins 9 on the hooks, thus placing the line again in a condition to be used by any other subscriber thereon.

Fig. 14 is a diagram illustrating the manner in which the magnets are energized. When any party on a party-line takes down his receiver to call central, he connects one side of his line with the ground at his telephone, as shown at 170. The other side of the line on the other side of the operating-magnets is already connected with the ground at central at 3. The calling party thereby energizes all the magnets on his line, thereby, as has been already explained, causing the line-controllers of the other parties on the same line to drop out of the position in which they can be caught by the automatic hooks. Then when central connects the line of the calling party on one side of the magnets with the corresponding side of another party-line by plugging in, she thereupon places the magnets of the second line in multiple on a circuit between ground at central and ground at calling party's telephone, and said other magnets are also energized, causing the gear-wheels to advance slightly, so that the line-controller cannot be caught by the automatic hook of any party on that line.

We claim—

1. In a selective telephone system, a party-line of which one wire grounds at central, a resistance therein at central greater than that of any talking-circuit in the system, means for connecting at central the other wire of said line with the corresponding wire of any other party-line of the system, selector-magnets at each station bridging the wires of the party-line, and means at each station for grounding said other wire, substantially as described.

2. In a selective telephone system, a party-line of which one wire grounds at central, a resistance therein at central greater than that of any talking-circuit in the system, means for connecting at central the other wire of said line with the corresponding wire of any other party-line of the system, selector-magnets at each station bridging the wires of the party-line, and means at each station for grounding said other wire, means, controlled by said magnets for throwing out all other talking-circuits except that of the station so grounded, substantially as described.

3. In a selective telephone system, a party-line of which one wire grounds at central, a resistance therein at central greater than that of any talking-circuit in the system, means for connecting at central the other wire of said line with the corresponding wire of any other party-line of the system, selector-magnets at each station bridging the wires of the party-line, and means at each station for grounding said other wire, means, controlled by said magnets preventing grounding at any other station, substantially as described.

4. In a selective telephone system, a party-line of which one wire grounds at central, a resistance therein at central greater than that

- of any talking-circuit in the system, means for connecting at central the other wire of said line with the corresponding wire of any other party-line of the system, selector-magnets at each station bridging the wires of the party-line, and means at each station for grounding said other wire, means, controlled step by step by successive energizations of magnets of the other line, for closing in succession the bell-circuits of said other lines, substantially as described.

5. In a selective telephone system, a party-line, one wire of which grounds at central, a resistance therein at central greater than that of any talking-circuit in the system, magnets at each station bridging said wire with the other wire of the line, means at each station for grounding said other wire, and means at central for connecting said other wire through an interrupter with the corresponding wire of any other party-line and also for inserting in the first wire at central an interrupter, whereby the magnets on either line can be intermittently energized by central, substantially as described.

6. In a selective telephone system, a party-line of which one wire grounds at central, a resistance therein at central greater than that of any talking-circuit in the system, magnets at each station bridging said wire with the other wire, means at each station for grounding said other wire, and means at central for inserting in said first wire an interrupter whereby the magnets can be intermittently energized, substantially as described.

7. In a selective telephone system, a party-line of which one wire grounds at central, a resistance therein at central greater than that of any talking-circuit in the system, magnets at each station bridging said wire with the other wire, means at each station for grounding said other wire, and means for inserting in said first wire an interrupter whereby the magnets can be intermittently energized, substantially as described.

8. In a selective telephone system, controlling mechanism comprising magnets and a rotating device advanced a short distance when a weak current passes through the magnets and a long distance in the same direction when a strong current passes therethrough and means for throwing a resistance into the line through the magnets by taking down the receiver, substantially as described.

9. In a selective telephone system, controlling mechanism comprising magnets and a rotating device advanced a short distance in the same direction when a weak current passes through the magnets and a long distance when a strong current passes therethrough and means operable by the calling party for throwing a resistance into the line through the magnets, substantially as described.

10. In a selective telephone system, controlling mechanism comprising a rotating device, clockwork mechanism for rotating the same, stops for the same arresting the device, the one after a long movement thereof and the other after a short movement, a magnet, means whereby the first stop is brought into action by a strong current through said magnet, and the second stop by a weak current therethrough, and means operated by taking down the receiver for throwing a resistance into circuit with the coil through the magnet, substantially as described.

11. In a selective telephone system, controlling mechanism comprising a rotating device, clockwork mechanism for rotating the same, stops for the same arresting the device, the one after a long movement thereof and the other after a short movement, a magnet, means whereby the first stop is brought into action by a strong current through said magnet, and the second stop by a weak current therethrough, and means operable by the calling party for throwing a resistance into circuit with the coil through the magnet, substantially as described.

12. In a selective telephone system, controlling mechanism comprising a rotating device, clockwork mechanism for rotating the same, arresting means therefor, a magnet for operating the latter, means for interrupting the currents through the magnet repeatedly in succession with a weak current, a circuit closed after a predetermined number of such interruptions, and means whereby a strong current through the magnet removes the arresting means to break said circuit, and arrests the rotating device in a subsequent position thereof, substantially as described.

13. In a selective telephone system, party-lines, one wire of each of which is grounded at central, a resistance therein at central greater than that of any talking-circuit in the system and the other wire of any line can be connected at central with the corresponding wire of any other line, means for grounding said other wire at any station of the line, and means whereby central can connect the two wires at any station on any line, to form a complete talking-circuit, substantially as described.

14. In a selective telephone system, a step-by-step rotating device, clockwork mechanism for rotating the same, a magnet controlling the same by interrupted weak currents therethrough, means for simultaneously closing the circuit through said magnet and throwing a resistance into said circuit to weaken the current to be subsequently so interrupted, means for shunting the resistance to pass a strong current through the magnet, means whereby said strong current returns the rotating device to its initial position, and means for holding the line closed upon operating the device.

ating said shunting means until said rotating device has returned to its initial position, substantially as described.

15. In a selective telephone system, a line-controller at each station, means for closing the circuit by said line-controller, means whereby the rise of the automatic hook operates the line-controller to close the circuit, means for supporting the line-controller in a position to be so operated by the rise of the automatic hook, and means whereby the closing of the circuit influences all the supporting means on the line to withdraw the controllers except the one already operated out of position to be so operated by the rise in the corresponding automatic hook, substantially as described.

16. In a selective telephone system, a line-controller at each station, means for closing the circuit by said line-controller, means whereby the rise of the automatic hook oper-

ates the line-controller to close the circuit, means for supporting the line-controller in a position to be so operated by the rise of the automatic hook, and means whereby the closing of the circuit influences all the supporting means on the line to withdraw the controllers ~~except~~ the one already operated out of position to be so operated by the rise in the corresponding automatic hook, and a busy signal brought into signaling position by such actuation of the supporting means, substantially as described.

In witness whereof we have hereunto set our hands in the presence of two subscribing witnesses.

NOBLE S. M. KINSEY.
ANTON R. NEISON.

Witnesses:

J. E. PARDEE,
RAY H. COLLINS.
